BREAST-STRAP FASTENER FOR INFANT CHAIRS

Albert B. Muller, Fort Wayne, Ind., assignor to
Juvenile Wood Products, Inc., a corporation
of Indiana

Application November 8, 1943, Serial No. 509,359

5 Claims. (Cl. 155—189)

This invention relates to improvements in breast-strap fasteners for infant chairs of the type having arm-rests supported in connection with a seat.

Generally breast-straps are secured to the arm-rests of infant chairs by means of snap fasteners on the ends of the breast-straps that are connected with screw-eyes driven into the arm-rests. Frequently, such connections are insecure because of the tendency of the screw-eyes to become loose, turn from one position to another, or pull out of place, thus permitting the occupant to fall from the chair.

An object of this invention is to afford an attachment for securing a breast-strap to the arm-rests of chairs in such manner that the attachment has separate connections with the arm-rest and the support therefor, thus to circumvent turning or dislodgment of the attachment.

Another object of the invention is to afford a breast-strap fastener for an arm-chair provided with means for securing said fastener individually to the arm-rest and the support therefor, thus to hold the fastener in a definite position on the arm-rest.

Other objects and advantages of the invention appear in the following description.

An illustrative embodiment of the invention is shown in the accompanying drawing, in which—

Fig. 1 is a view of an ordinary infant's arm-chair of a well-known type, equipped with the invention, the view being a longitudinal section;

Fig. 2 is a fragmentary front elevational view projected from Fig. 1;

Fig. 3 is an enlarged fragmentary top plan view of an arm-rest to which the invention is attached;

Fig. 4 is a side elevational view of the structure shown in Fig. 3; and

Fig. 5 is a perspective view of a fastener embodying the invention.

An illustrative embodiment of the invention preferably consists of a fixture formed of wire shaped to provide an elongated loop 1 for the reception therethrough of a breast-strap 2, a radially extending threaded end portion 3 contiguous with one terminal of the loop, and a laterally extending portion 4 contiguous with the other loop terminal having an eye 5 formed at its outer end constituting an anchor.

In Figs. 1 and 2 is shown a folding arm chair to which the invention is applicable, the chair consisting of a seat 6, folding back-rest 7 pivoted on the seat, arm-rests 8 connected at their rear ends to the back-rest by pivots 9, and sup-

ported at their forward end portions by links 10 that are connected at their opposite ends respectively with said arms and seat by pivots 11 and 12.

5 The breast-strap fixtures are secured to the arms of the chair by first screwing the threaded portions 3 directly into the arms, then placing the eyes 5 of the anchors correspondingly between the arms and the upper ends of the links 10, and finally driving the pivot screws 11 through the perforated upper end portions of the links 10 and the interposed anchor eyes 5 into the arms 8. In this manner the fixture is supported by its threaded portion which is secured in the arm-rest and also by its anchor which is secured in connection with the arm-rest and the supporting link by the pivot screw therefor, so the fixture is held in a definite selected position on the arm-rest and is thus prevented from turning upon the axis of the threaded portion or becoming accidentally detached from the chair. The anchor eye being disposed on the pivot screw between the arm-rest and the link prevents relative movement of the fixture with respect to the arm-rest while permitting the link to turn upon the pivot screw when folding or unfolding of the chair.

20 Variations from the particular construction above disclosed may readily be made by exercise of engineering skill without departure from the spirit or scope of the invention, and the following claims are intended to be inclusive of such variations.

25 What I claim is:

1. A fixture for attachment of a breast-strap to the arm-rest of a chair where the arm-rest has a supporting link secured thereto by a pivot screw, said fixture being formed of wire shaped to provide a loop for reception therethrough of a breast-strap, a radially extending threaded portion contiguous with one terminal of said loop, and a laterally extending portion contiguous with the other loop terminal provided at its outer end with an eye constituting an anchor, the arrangement being such that when said threaded extension is screwed into the arm-rest and said anchor is secured on the pivot screw, said fixture is held in a definite selected position on the arm-rest.

2. A fixture for securing a breast-strap to the arm-rest of a chair where the arm-rest has a supporting link and a pivotal connection for said link, said fixture having a loop for attachment of a breast-strap, an extending threaded portion contiguous with one terminal of the loop adapted to be screwed into said arm-rest and a laterally

extending anchor contiguous with the other loop terminal adapted to be secured on said connection wherefore said fixture is held in a definite selected position on said arm-rest.

3. In an arm chair structure having an arm-rest and a supporting link and a connection to secure the link and arm-rest together, a fixture provided with a loop for attachment of a breast-strap, a radially extending member threaded in said arm-rest and a laterally extending anchor member secured on said connection to prevent turning movement of said fixture relative to said arm-rest.

4. In an arm chair structure having an arm-rest and a support therefor, a fixture having a loop for attachment of a breast-strap provided with an extension threaded in said arm-rest and

an anchor member extending between said support and arm-rest, and means connecting said support, anchor and arm-rest together wherefore to hold said loop in a definite selected position on the arm-rest.

5. A fixture for attachment of a breast-strap to the arm-rest of a chair, said fixture having a loop adapted for connection of a breast-strap thereto, provided with a projecting member adapted for threaded engagement in said arm-rest, and an angularly extending member secured to said arm-rest at a point thereon spaced apart from the other member wherefore to prevent turning of said loop from a definite selected position on said arm-rest.

ALBERT B. MULLER.
